UNITED STATES PATENT OFFICE.

ANDREW HOWARD, OF WILKINSBURG, PENNSYLVANIA.

DESIGN FOR A CHIMNEY.

SPECIFICATION forming part of Design No. 32,029, dated December 26, 1899.

Application filed September 8, 1899. Serial No. 729,888. Term of patent 7 years.

To all whom it may concern:

Be it known that I, ANDREW HOWARD, a citizen of the United States, residing at Wilkinsburg, in the county of Allegheny and State of Pennsylvania, have invented a certain new and useful Design for Chimneys for Gas-Burners, &c.; and I do hereby declare the following to be a full, clear, and exact description of the invention, such as will enable others skilled in the art to which it appertains to make and use the same.

My design has relation to glass chimneys.

In the accompanying drawings, illustrating my design, Figure 1 is a side view of a chimney. Fig. 2 is a plan view, and Fig. 3 is a transverse section, of the chimney on the line $x x$ of Fig. 1.

The chimney made according to my design consists of the cylindrical body A, which merges by the curve B into the rounded ²⁰ shoulder C.

Having described my invention, I claim as new and desire to secure by Letters Patent—

The design for a chimney herein shown and described. ²⁵

In testimony whereof I affix my signature in presence of two witnesses.

ANDREW HOWARD.
